(57) **CLAIM**

The ornamental design for a novelty greeting card, as shown and described.

DESCRIPTION

FIG. 1 is a front elevational view of the novelty greeting card of the present invention;

FIG. 2 is a rear elevational view of the novelty greeting card of FIG. 1;

FIG. 3 is a left side elevational view of the novelty greeting card of FIG. 1;

FIG. 4 is a right side elevational view of the novelty greeting card of FIG. 1;

FIG. 5 is a top plan view of the novelty greeting card of FIG. 1; and,

FIG. 6 is a bottom plan view of the novelty greeting card of FIG. 1.

The broken line showing of letters in FIGS. 1 and 4 is for illustrative purposes only and form no part of the claimed design.

1 Claim, 3 Drawing Sheets

FIG. 2

FIG. 1

FIG. 3

The first time you touched
me in that single moment,
I became yours forever
And though we can never
recreate that exact
moment in time, what
we share together now
is even better.

FIG. 4

FIG. 5

FIG. 6
